Inventor:
Anthony Shacikoski

UNITED STATES PATENT OFFICE.

ANTHONY SHACIKOSKI, OF HOMER CITY, PENNSYLVANIA.

COMBINED TROLLEY WIRE AND GUARD HANGER.

Application filed May 6, 1924. Serial No. 711,512.

To all whom it may concern:

Be it known that I, ANTHONY SHACIKOSKI, a citizen of the United States, residing at Homer City, in the county of Indiana 5 and State of Pennsylvania, have invented certain new and useful Improvements in Combined Trolley Wire and Guard Hangers, of which the following is a specification.

My invention relates to improvements in 10 hangers, and more particularly to a combined trolley wire and guard hanger especially designed for use in coal mines.

In practice, the trolley wire hangers now 15 so generally employed in coal mines are in many instances secured directly to the coal or rock, constituting the roof of an opening, and under my invention I also secure the hangers to the roof.

It is required by mining laws, that the 20 trolley wire be protected especially at crossovers to prevent operators from coming in contact therewith, and this protection has been attempted to be accomplished by the employment of "guard boards" disposed on both sides of the wire, and projecting below the plane in which the wire is located, which boards are held in place by means of independent wooden plugs, and brackets fixed over the insulators. However, 25 considerable trouble has arisen from the use of the "guard boards", due to the inability to keep them in the desired position, inability to prevent mine fires due to the metal brackets coming in contact with the wire and 30 grounding the roof, also endangering operators of coming in contact with the charged bracket. Again if the insulator should become grounded due to defect, then the bracket around the board would become 35 charged, and this would create a dangerous condition. The difficulty of putting wires in clamps, after they come out at places where guard boards are employed, and are held in place by means of brackets. The 40 expense, dangerous conditions and difficulty of putting up or placing guard boards are encountered.

The prime objects of the present invention are to provide a simple and efficient means 50 for supporting securely and safely these guards, and at same time to lessen the difficulty, labor, dangerous conditions to property and life, and expense of placing the guards in position; and to provide a new 55 and improved combined trolley wire and guard hanger construction.

In the accompanying drawings, which illustrate an application of my invention;

Fig. 1 is a transverse sectional view embodying my invention.

Fig. 2 is an enlarged section of the bracket and head.

Fig. 3 is a prospective view of a guard supporter, showing how easily it would be to remove obstruction when working on 65 wire.

Fig. 4 is a plan view of the bracket or top of insulator.

Fig. 5 is a sectional view of the insulated connection of the guard supporter and 70 bracket hook.

Fig. 6 is a side elevation of the insulated connection of the guard hook, this is what insulates the guard supporter from the bracket or insulator.

Referring to the drawings, 1 designates the roof of an opening in a coal mine, the opening being designated to permit the passage of electrically propelled vehicles; 2 the trolley wire, and 3 the anchor structure of 80 the hanger may be of any desired construction capable of being securely attached to the roof 1. As illustrated, it includes an outer hollow split casing or sleeve 4, an interiorly disposed wedge shaped nut 5, said 85 nut having its central bore threaded, and an exteriorly threaded rod or bolt 6. The threads of bolt 6 are adapted to engage with the threads of the nut 5 for the purpose of adjusting said nut within the split hollow 90 sleeve as desired.

As shown the anchor structure is designed to be positioned within a pre-formed hole in the coal roof. Detachably secured to the lower end of the bolt 6 of the anchor structure is a head 7, 8 designates a clamp device adapted to engage the trolley wire 2, said clamp being connected with the head 7 by means of the threaded member 9. The top of the threaded member is of an oval shape 100 11 and fits into the head through an oval shaped hole 10, and then it is turned, so that it will not drop out. The member 9 and its head 11 are insulated by means of a mica casing around the head 11, and packed with 105 insulating compound 50 made up of asbestos fiber, rubber and other insulating fibers. 12 is a brace integral with the head 7, and this brace helps to support the top of the head 7 at the ends of which are threaded bores 13 for the reception of the threaded end hook 14, which holds the guard board 110.

in position by means of a pointed set screw 16, which works within the threaded bore 17. 18 is the threads of the bore in head 7. These threads correspond with the threads 5 on bolt 6. The threaded bore 18 has a reservoir or space 19 for cotton saturated with oil, which when the 6 turning into the threaded bore 18 compresses the cotton saturated with oil and forces oil out of the saturated cotton in reservoir 19 up along the 10 groove 20 cut through the threads in the bore 18, this process oils the threads and preserves them from rust.

Into the threaded bores 13 is screwed in 15 or turned in, an insulating block 21. The threaded metallic surface 21 is insulated from the inner threaded core 25 by means of the insulation 24. The threads 22 of the metallic core 25 are made for the reception 20 of the threaded end 23 of the supporting hook 14. 26 is a shoulder so fixed in the exterior threaded casing 21, that the oval head 28 of the interior threaded core 25 rests above the shoulder 26 with the insulation 24 between them. The opening 29 between the shoulders 26 is of an oval shape similar to the head 28 of the core 25 only it is larger, so that the oval head 28 will pass through the oval opening 29 and the core 30 25 is turned in any direction, so that the oblong end of the oval head 28 is over the short diameter of the oval opening 29. This makes the insulator block more substantial.

From the above, it will be apparent, that 35 I have provided a simple and efficient structure for supporting the trolley wire and the guards and that the assembled structure may be positioned as a unit, and when not assembled it may be only used for the wire, where 40 the guards are not necessary, but when guards are required it is all assembled as a unit, thereby eliminating the employment of separate means for supporting the wire and the guards. Further, that the guards will 45 always be maintained in the desired posi-

tions relative to the wire. The insulator alone will not rust to the anchor structure and there by when wire is taken down, the insulators will be easy to disconnect from the anchor structure, due to the automatic 50 oiling system. The dangers of the mine fires due to guard board bracket grounds is over come by the insulating block or connection between the guard hook and the main insulator.

What I claim is:

1. In a combined trolley wire and guard hanger, the combination with an anchor structure, of means carried by the anchor for supporting a trolley wire guard, said latter supporting means including a bracket having spaced apart two threaded bores for the reception of the insulator block or connection, said insulator connection having a threaded bore in the center, which is insulated from the outside, a guard supporting hook having a threaded upper end adapted to be threaded into said center bore, and a set screw adapted to secure the guard to the said hook.

2. A trolley hanger for mines comprising a bracket embodying oppositely projecting guard hooks, which are insulated from the bracket by means of insulator blocks, an insulator head, the insulator head being formed with a downwardly projecting stud bolt whose oval head is fitted into oval socket of insulator head, the upper face of the bracket above the insulator head, being formed with a downwardly projecting screw threaded socket, having an oil packing reservoir at bottom, small trench leading from reservoir up across the threads, the outer ends of bracket being formed with threaded bores for the reception of insulator blocks, and these blocks in turn to receive the threaded ends of the guard hooks, which support the guards in their position by means of set screws.

ANTHONY SHACIKOSKI.
